US00D997034S

(12) **United States Design Patent** (10) Patent No.: **US D997,034 S**
(45) Date of Patent: **** Aug. 29, 2023**

(54) **BUS**

(71) Applicant: **Volvo Group Canada, Inc.**,
Sainte-Claire (CA)

(72) Inventors: **Francois Trepanier**, Quebec (CA); **Luc Bourgeois**, Ste-Therese (CA);
Christian Héroux, St-Constant (CA)

(73) Assignee: **VOLVO GROUP CANADA, INC.**

(**) Term: **15 Years**

(21) Appl. No.: **29/818,992**

(22) Filed: **Dec. 13, 2021**

(51) LOC (14) Cl. **12-08**

(52) U.S. Cl. **D12/84**
USPC ....
